UNITED STATES PATENT OFFICE.

CONSTANT J. KRYZANOWSKY, OF MOUNT WASHINGTON, MARYLAND, ASSIGNOR TO
THE CROWN CORK AND SEAL COMPANY OF BALTIMORE CITY, OF BALTIMORE,
MARYLAND, A CORPORATION OF MARYLAND.

CLOSURE-APPLYING APPARATUS.

Application filed May 31, 1917. Serial No. 171,921.

To all whom it may concern:

Be it known that I, CONSTANT J. KRYZANOWSKY, a citizen of the United States, residing at Mount Washington, county of 5 Baltimore, and State of Maryland, have invented certain new and useful Improvements in Closure-Applying Apparatus, fully described and represented in the following specification and the accompanying drawings, forming a part of the same.

The present invention relates to improvements in machines for applying closures to receptacles and particularly to a bottle capping machine, such, for example, as a machine for applying the usual crown closures 15 to bottles.

One of the principal objects of the invention is to provide a machine capable of applying closures at a higher rate of speed 20 than has heretofore been practicable with machines previously known.

A further object of the invention is to provide a machine which can be adjusted to work in connection with any one of a plurality of types of fillers, such as are now 25 on the market, thereby avoiding the necessity of specially constructing a closure-applying machine for the particular type of filler with which it is to operate.

Another object of the invention is to provide a bottle capping machine in which the percentage of loss due to breakage of bottles or imperfect capping will be reduced notwithstanding the high speed of operation.

With the above general objects in view and some others which will be obvious to those skilled in the art from the description hereinafter, the invention consists in the 40 features, details of construction and combinations of parts which will first be described in connection with the accompanying drawings illustrating one embodiment of the invention, and then more particularly pointed out.

In the drawings—

Figure 1 is a side elevation partly in section of a bottle-capping machine embodying the invention in its best form;

Figure 2 is an enlarged vertical section, partly in elevation, through the head casing and its contained mechanism;

Figure 3 is a horizontal section through the head casing on the line 3, Fig. 2;

Figure 4 is a similar view on the line 4, 55 Fig. 2;

Figure 5 is an enlarged detail sectional view illustrating the compensating mechanism, a pair of cam rollers, and one of the presser-rod locking and unlocking devices; 60

Figure 6 is a detail sectional view of a part of the presser rod locking mechanism, this view being taken at right angles to the view of the corresponding parts in Fig. 5;

- 15 Figure 41 is a broken plan view, partly in section, showing the table mechanism and the arrangement of the same relative to the transmission mechanism and the conveyors;
- Figure 42 is an enlarged detail plan view, 20 partly broken away, of the table and feed mechanism;
- Figures 43, 44 and 45 are detail views illustrating the cage;
- 25 Figure 46 is a detail front elevation of the crown hopper and crown distributing mechanism;
- Figure 47 is a detail view partly in section of the locking hinge mechanism for the head casing;
- 30 Figures 48, 49 and 50 are detail views illustrating the means for collecting oil at the bottom of a plunger and pumping it back to the head casing.
- The apparatus shown as the preferred embodiment of the invention comprises a suitable support or pedestal, a head casing adjustable vertically with relation to the support and carrying the capping mechanism and the means for supplying closures there- 35 to, a bottle supporting device, or table mechanism, adjustable with relation to the support, suitable transmission mechanism for transmitting power to drive the machine, feed mechanism for supplying receptacles to the capping means, means for removing the capped receptacles, and means for lubricating the moving parts.
- The head casing is so constructed and the capping mechanism is so mounted within it 40 that the latter may be removed from the casing as an entirety. In the present embodiment of the invention the casing is divided vertically into two parts, one of which, for example the front part 1, is removed from, but advantageously hinged to, the other part 2. In the present example, the line of joinder is made oil-tight in any suitable way, as, 45 for example, by grooving the meeting edge of the part 1, and inserting a compressible packing 3 therein. See Figs. 2, 3 and 4.
- For the purpose of hinging the front part 1 to the part 2 of the head casing in such a manner as to permit it to be swung back in either direction as desired, or to be removed 50 from the part 2, a special forming of con-
- necting device is employed. In the present example, two of these connecting devices are employed, one on each side of the head casing. Each connecting device comprises a pair of lugs 4, Fig. 47, fixed to the rear part 70 2 of the head casing and arranged to receive eye-bolts 5 and 6, the upper one, 5, being slotted in a vertical direction and having an upward extending conical end as indicated at 5^a, Fig. 47.
- The front 1 of the casing has a pair of lugs 7 and 7^a with vertical openings. In these openings is mounted a vertically slide- 75 able pintle bar or rod 8, provided with a handle 9 by which it may be manipulated. At the upper end of the pintle rod 8 is fixed a cap 10 having a conical socket arranged to fit down upon the upward extending coned end 5^a of the upper eye-bolt 5. At a suitable point, as, for example, above the upper lug 7^a of the front 1, the pintle bar 8 is provided with a cam latch 11, fixed to the rod and arranged to swing beneath the upper eye-bolt 5, this latch having its upper surface inclined to engage a correspondingly inclined portion on the eye-bolt 5. The lower end of the pintle rod 8 is arranged to enter the eye of the lower eye-bolt 6, and at this time the cap 10 will engage the coned end 5^a of the upper eye-bolt 5. By then rotating the 80 pintle-bar 8 by means of the handle 9 the cam latch 11 is brought into engagement with the inclined surface of the upper eye-bolt 5, so that the pintle bar is locked against upward movement and the cap is drawn 85 down tightly onto the coned end 5^a. By rotating the pintle bar in the direction to swing the latch 11 from under the upper eye-bolt 5, and then lifting the bar, the cap 10 is freed from the coned end 5^a while at 90 the same time the lower end of the bar is lifted out of the lower eye-bolt 6. In this position the connecting device is open and unlocked. As there are two such connecting devices, one at each side of the head casing, 95 it is obvious that if one is unlocked, the front part 1 of the head casing may be swung outward like a door, so as to permit access to the interior mechanism. Since either connecting device may be unlocked and the other allowed to remain in the locked position, the front part 1 of the head casing may be 100 swung in either direction as desired. Furthermore, by unlocking both connecting devices simultaneously, the front part 1 may be 105 entirely removed. Each of the pintle bars 8 may be provided at its lower end with a suitable cotter device, indicated at 8^a, Fig. 47, which prevents the accidental movement of the respective pintle bars in an upward 110 direction. By proper adjustment of the nuts on the eye-bolts 5 and 6, the front part 1 may be arranged to fit tightly against the elastic packing 3 between the two parts of 115 the casing.

The capping mechanism comprises a frame work which may be termed a cage, consisting, in the present example, of a top spider 12, Figs. 43 and 44, a bottom rim 13, 5 and arms 14 connecting these two. To the bottom rim 13 of the cage is secured a removable bottom bearing plate 15, Fig. 45, which is provided with bearings for mechanism hereinafter described. The cage is secured to a shaft 16 which is mounted in a single bearing at the top of the head casing in such a way that when the casing is opened along its dividing line and the bearing released from the rear part 2 of the casing, the shaft 10 16 with its bearing and the cage 12, 13, 14 with all of its connected parts and mechanism, may be removed through the open front of the casing. The bearing for the upper end of the shaft 16 comprises a hollow boxing 17 arranged to be bolted to the rear portion 2 of the casing by bolts, one of which is shown at 18, Fig. 2. The upper end of the shaft 16 is provided with ball bearings whose raceways are carried 15 within the boxing 17. A suitable cap 19 is secured in the upper end of the hub and arranged to be locked by a set screw 20. To the cap 19 is threaded a large eye-bolt 21, Fig. 1, to which may be attached suitable 20 tackle for the purpose of holding the shaft 16, the cage, and the mechanism carried thereby, when swinging these parts out of and into the head casing. The shaft 16 is tubular at its lower end and into this tubular part telescopes a table drive shaft 22 the purpose of which will be more fully described hereinafter in connection with the description of the table mechanism. The shaft 22 is arranged to be rotated with the 25 shaft 16 in any suitable way, as, for example, by providing the shaft 22 with keyways on opposite sides in which enter keys, indicated at 23, Fig. 2. By this arrangement the shaft 22 and the shaft 16 may be moved relatively to each other in an axial direction while at the same time always rotating in unison. The invention in its entirety includes a reciprocating capping plunger, a relatively movable abutment, 30 bodily and angularly movable driven means bodily moved with a fixed stroke, and means whereby the force of said movable means is applied to the capping plunger to lower the same as long as a predetermined force 35 is not exceeded and is thereafter transferred to the abutment to move the latter and to release the plunger. In multi-head machines, such as the present exemplification, the abutment may be common to the several 40 heads. That is, there is provided a plurality of capping heads, a common compensating spring and means for successively bringing the capping plungers into operative relation with this spring. Although capable of various constructions, in the present exemplifi- 45 cation, upon the shaft 16 is mounted a triangular abutment block 24, Figs. 2 and 4, provided with three pairs of racks, as indicated at 24^a, for a purpose hereinafter explained. The upper end of the abutment block 24 is cylindrical and enters a corresponding opening in a spider 25 having two arms 25^a and 25^b, extending in radial directions. The spider 25 is held to the abutment block 24 in any suitable way, as, for example, by a bolt 26, Fig. 2. To the top spider 12 of the cage is secured a downward depending spring hanger bar 27 which extends downward through the opening in the outer end of the bar 25^a and is surrounded by a spring tube 28. In the lower end of this tube is threaded a bushing 28^a, against which bears a nut 29 on the lower end of the hanger bar 27. The bushing 28^a has an outward extending flange upon which rests a helical spring 30 whose upper end bears against the upper side of the arm 25^a. The lower ends of the spring and the hanger bar extend through an opening in the bottom bearing plate 15, this opening being threaded to receive a hollow cap 15^a which covers the lower ends of the spring and hanger bar. The upper end of the spring tube 28 is flanged outwardly, as shown, so that this flange may engage and hold the spring 30 when the hanger bar, tube and spring are removed from the cage. The top spider 12 has an upwardly extending hub, as indicated at 12^a, Fig. 2, which enters the central opening in an upper bearing plate 32 having upper bearings 33 for capping plungers hereinafter more fully described. Upon this top bearing plate 32 is mounted a spacer 34 surrounding the shaft 16 at its upper end and provided with three radially extending lugs 34^a at its lower end. Through these lugs and through holes in the upper bearing plate 32 and through the top spider 12 of the cage are passed bolts 35 whereby the spacer, the upper bearing plate and the cage 100 are secured together. The lower bearing plate 15 is provided with openings having bushings 36 in line with the corresponding upper bearings 33. In the corresponding upper bearings 33 and bushings 36 are 105 mounted capping plungers, one of which is indicated at 37, Fig. 2. These capping plungers are constructed as hollow cylinders containing certain parts of the capping mechanism, as will more fully be described 110 hereinafter. These plungers are arranged to be moved vertically, so that as the cage rotates each plunger in turn will be moved downward to cap a bottle and then recede therefrom in order that the bottle may be 115 removed. 120

For the purpose of performing this function, as well as some others as more fully explained hereinafter, the following mechanism is illustrated as an example. To each 130

plunger 37 is secured a sleeve 38 (Fig. 5) having a pair of upward extending rack bars 39, the racks facing a corresponding pair of racks 24^a on the abutment block 24. 5 Each plunger passes slidably through an opening in a corresponding head 40 extending inward radially from a yoke 41, having upward and downward extending guide portions 42 and 43, respectively. The upward 10 extending guide portion 42 of each yoke is vertically movable in an opening in the top bearing plate 32. The downward extending guide portion 43 of each yoke extends into a cylindrical portion 44 carried by the bottom bearing plate 15. Each yoke carries a 15 pair of cam rollers 45 and 46. The lower roller 45 of each yoke rotates upon a stud 47, fixed in a bearing carried by the yoke, and carrying a ball raceway 48. Between 20 the cam roller 45 and this raceway 48 suitable balls are inserted, as shown at 49, Fig. 5. The upper cam roller 46 is mounted in a special manner for purposes hereinafter more fully described. This mounting comprises 25 a stud 50 on which the ball raceway 51 is mounted, suitable balls 52 being inserted between the raceway 51 and the cam roller 46. The portion of the stud 50 which carries the raceway 51 is eccentric to the 30 axis of the stud. The outer end of the stud 50 is provided with a portion 51^a. This portion fits in a corresponding opening in the yoke and has an arm 53 outside the yoke (see Figs. 5 and 11). The arm has an eye 35 loosely engaging a bolt 53^a hanging down from a lug 54 carried by the yoke. The bolt is surrounded by a spiral spring 55 which bears against the bottom of the lug 54 and the top of the arm 53. It will be 40 noted that by this mounting of the upper cam roller 46 any heavy pressure on the roller on the eccentric portion 50 of the stud will tend to rotate the stud and thereby tend to swing the arm 53. This tendency is 45 resisted by the spring 55. The head of the bolt 53^a limits the downward angular movement of the arm 53 and by adjusting the nut on the bolt the minimum distance apart between the cam rollers 45 and 46 may be 50 fixed. The cam rollers are arranged to ride against a circular cam 56, Fig. 5, which is provided with an outwardly extending flange or rib 56^a arranged to enter a rabbet in a cam housing 57. This housing has a 55 downwardly extending cylindrical skirt, as shown in Figs. 1 and 2, whereby the housing is given a great strength in a downward direction. The housing is also provided with a flange 57^a arranged to enter a 60 groove formed in an inwardly projecting rib 2^a carried by the rear portion of the casing 2. The cam ring 56 is held to the cam housing by pins 56^b, Fig. 2. For the purpose of holding the cam housing 57 securely to the rear portion 2 of the head cas- 65

ing, and at the same time permitting ready removal therefrom, the flange 57^a is provided with notches, as shown in Fig. 3, into which notches enter the heads 58^a of bolts 58 passing through lugs 2^b formed in the rear portion 2 of the casing. When these bolts 58 are drawn up tightly they clamp the cam housing 57 tightly in the rib 2^a, as will be clear from Fig. 3. By loosening nuts on the bolts 58 and rotating said bolts 70 on their axes, their heads 58^a are freed from the notches in the flange of the cam housing, so that then the cam housing 57 and the cam 56 may be removed outward with the cage and its connected parts to remove 75 the mechanism through the front of the casing.

The cam 56 has about two-thirds of its upper and lower cam surfaces in horizontal planes, while slightly less than one-third 80 constitutes a depressed portion down and up which the respective pairs of cam rollers 45, 46 move to operate the corresponding plungers. By this arrangement in a capping machine having three capping plungers, as illustrated in the embodiment of 85 the invention, there are always two sets of cam rollers running on a horizontal portion of the cam, while the third set of cam rollers is running on the depressed portion of 90 the cam to operate the plunger. The two sets of cam rollers on the horizontal portion of the cam serve to assist in supporting the cage, so that practically no vertical thrust comes upon the bearing at the upper 95 end of the shaft 16. Each head 40 of the respective yokes carries a pair of journals 40^a, on which are mounted pinions 59 (Fig. 4), each pair of pinions engaging with the racks 39 of the respective plungers and with 100 the corresponding pair of rack portions 24^a of the abutment block 24. Consequently, as the cage is rotated by means hereinafter described, and as the cam rollers 45, 46 of each plunger ride down the depressed portion of 105 the cam, the arms 40 will carry their pinions 59 downward. As these pinions are in engagement with the racks of the abutment block and as this abutment block is forced upward by the spring 30 against the bottom 110 of the top spider 12 of the cage, the pinions 59 will rotate and thereby force the rack bars 39 of their respective plunger downward. The downward motion of the plunger will be twice as rapid as the downward 115 motion of the corresponding yoke 41 when riding down the depressed portion of the cam. It will be noted that if the lower end of the plunger encounters a sufficiently great resistance to downward movement, this will 120 react through its rack bars 39 and the corresponding pinions 59 against the coacting rack portions of the abutment 24, and thereby tend to drive this abutment block 24 125 downward and compress the spring 30. 130

This is termed the compensating action for the plungers, since in this way the amount of pressure which can be brought to bear in capping a bottle is a maximum fixed by the pressure necessary to compress the spring 30. It will be noted that when the abutment block 24 is moved downward by the action of the pinions of the plunger, it will tend to rotate the pinions of the other two plungers so as to lift said plungers, hence the maximum pressure for capping a bottle is not merely that due to the spring 30, but includes that due to the weight of the other two plungers not at that time in capping operation. As the one spring 30 serves for compensating all three plungers, the great advantage is attained that the maximum pressure of each capping plunger during its capping action is the same as that of each of the others. In prior constructions, it has been customary to provide each capping plunger with its own spring. This has led to many difficulties, since in practice it is impossible to construct compensating springs of uniform resiliency. Hence, by the use of the one compensating spring for a plurality of capping heads, it becomes possible to obtain a uniformity of action of each capping plunger hitherto unattainable and very important in a high speed machine. Furthermore, as the cam track is arranged to surround the capping plungers, the length of the cam may be made sufficient to allow an easy rise and fall of the depressed portion of the cam for the given angular movement of the rotating mechanism during the capping operation. This prevents the sudden shocks which would result from an abrupt depression of the cam, such as would be necessary if the cam were within the orbit of the capping plungers.

In view of the eccentric mounting of the upper cam rollers 46 it becomes possible to use a construction of the kind described without the great amount of lost motion which would otherwise be necessary. As the cam is likely to wear unequally, the eccentric mounting of the upper rollers allows them to follow the variations in surface of the cam and thus prevent the vibrations due to the uneven cam wear which would otherwise occur, or the undue friction and sticking which would occur if the rollers 45 and 46 were rigidly mounted too closely together. For the purpose of causing the rotation of the cage and the parts carried thereby, any suitable driving means may be employed. In the particular embodiment of the invention illustrated in the drawings, the rotation of the cage is accomplished in the following manner: An annular gear wheel 60 is secured to the bottom ring 13 of the cage in any suitable way, as, for instance, by providing the bottom ring 13 with an upwardly projecting flange extending in-

side the annular gear wheel 60 and providing bolts 61 extending through lugs carried by the annular gear wheel 60 and through the bottom bearing plate 15, as will be clear from Fig. 45. The annular gear wheel 60 is engaged by a pinion 62 which projects through an opening in the rear wall of the rear part 2 of the head casing. The pinion 62 is driven by means hereinafter more fully described. For the purpose of steadyng the rotating cage laterally, a plurality of rollers 63, for example, three, as shown in Fig. 4, are mounted on the cage and arranged to engage the inside surface of the cam housing 57.

Each plunger 37 is provided at the lower end with the usual capping die 37^a and carries in its interior a mechanism which may be called a presser foot or presser rod. This presser rod, indicated at 64 in Fig. 2, is made in sections for the purpose of conveniently assembling the mechanism and carries a plurality of collars 65, 66. The presser rod is surrounded by three springs 67, 68, 69. The lower spring 67 bears against a sleeve 70 arranged to engage the collar 65. The upper end of this spring bears against a sleeve 71, whose upper surface is engaged by the lower end of the spring 68. The upper end of the spring 68 in turn engages the bottom of a sleeve 72 whose upper surface is engaged by the lower end of the spring 69. The upper end of the spring 69 engages the lower surface of a sleeve 73 whose upper flange surface is arranged to contact with the collar 66 and with the lower end of a shoulder formed in the plunger 37. In the present example this shoulder is formed as follows: The plunger 37 is made in two parts, these two parts being in telescopic relation, the upper part being threaded into the lower part, as more clearly appears in Fig. 2. The upper part below the threaded portion is provided with a downwardly extending skirt 37^b, the bottom of which forms the above mentioned shoulder engaged by sleeve 73. Above the collar 66 the presser rod is surrounded by an extension tube 74 to which the presser rod is secured by a transverse pin 74^a, Fig. 5. This tube is arranged to be engaged by locking devices which in the present example comprise rollers 75, loosely mounted in openings in a vertically movable roller carrying head 76 whose lower portion is formed as a cylindrical skirt slidable in a corresponding opening formed in the top bearing spider 32. The rollers 75 are arranged to be engaged by inclined surfaces carried by an abutment device 77 suitably secured to the top bearing spider. A spring 78 inserted between the roller-carrying device 76 and the top bearing spider tends to force the roller-carrying device upward to bring the rollers 75 into engagement with the in-

clined surfaces of the abutment device 77, and thereby force said rollers into locking engagement with the tube 74. It will be noted that the plunger is free to move downward, because then the tube 74 tends to move the rollers 75 and their carrying device 76 downward against the action of the spring. If, however, any pressure comes upon the presser foot in an upward direction, the rollers 75 will lock the presser foot against upward movement.

The top of the plunger 37 carries an adjustable stop device consisting in the present example of a tubular rod 79 screw threaded through the top of the plunger and provided with a head 79^a having holes to receive a spanner, whereby the tubular rod may be adjusted up or down as required. As a result of the particular construction described, the presser rod 64 is normally held with its lower end projecting a slight distance into the crowning die. When the plunger 37 is forced to descend, the presser rod 64 and plunger travel down together as a unit, until the crown, picked up by the bottle, comes in contact with the bottom end of the presser rod. The rod stays on the crown on the head of the bottle while the plunger 37 travels down a sufficient distance to complete the crowning operation in the usual way. In practice this travel of the plunger after the presser rod has contacted with the crown is about five-eighths of an inch. During this time the springs 67, 68 and 69 surrounding the presser rod are compressed. At the completion of this independent downward movement of the plunger the upper end of the presser rod contacts with the bottom of the stop device 79. At this point, the presser rod 64 and plunger 37 become a unit. Any further movement downward of these parts will be resisted by the bottle and thereupon the compensating action takes place, as will be clear from the description hereinbefore given.

At the completion of the downward stroke of the respective cam yoke 41 it then commences to move upward. If there has been any compensating action of the abutment block 24 and its spring 30, the depressed plunger does not immediately leave the bottle but the first action is the return of the abutment block 24 to its normal position by the spring 30. Thereafter the plunger 37 starts on its upward movement, but at this time the presser rod 64 is prevented from returning and is held on top of the crowned bottle by means of the locking device at the upper end of the presser rod, that is, the rollers 75 are forced against the tube 74 at the upper end of the presser rod by the inclined surface of the abutment device 77. This results in holding the bottle firmly against the table until the plunger

37 has returned to within a very short distance of the upward limit of its stroke. In practice, the presser rod 64 stays in contact with the crowned bottle until the plunger 37 has completed all of its upward stroke with the exception of about one-fourth of an inch. This prevents any possibility of the bottle being lifted by the crown catching in the die.

As soon as the die portion 37^a of the plunger is entirely free from the bottle, which occurs when the lower surface of the crowning die is above the lower end of the presser rod it becomes necessary to release the presser rod 64 from its locked position and allow it to be carried upward by its springs. To accomplish this result, suitable means is provided for forcing the roller-carrying device 76 in a downward direction against the action of its spring 78. In the present example, this means consists of a lever 80 suitably pivoted on the top bearing spider and having a forked end which straddles the tube 74, the upper end of the plunger 37 being cut away at each side to permit this, as shown in Fig. 10. The lever 80 engages the top surface of the roller-carrying member 76. The outer end of the lever 80 is above and in line with the upper guide member 42 of the corresponding yoke. This upper guide member is provided with a set screw 81 having a lock nut 81^a whereby the set screw may be adjusted as desired and locked in any desired position. The upper end of the set screw contacts with the outer end of the lever 80 at the proper moment and thereby swings the lever so as to push the roller carrying device 76 downward against the tension of its spring 78 and release the roller 75 from the inclined surface of the abutment member 77, so that the tube 74 and the presser rod 64 are free to move upward under the action of the springs 67, 68, 69.

For the purpose of locking the lever 80 to hold the roller carrying device 76 in its unlocked position, a suitable latch device is provided. This consists of a latch lever 82 pivoted to the outer end of the lever 80 and provided with a locking shoulder 83 arranged to engage a corresponding shoulder 84 carried by the top bearing spider, as shown in Fig. 2. The latch lever is acted on by a spring 85 which tends to draw the shoulder 83 in engagement with the shoulder 84, so that when the outer end of the lever 80 is moved upward by the action of the corresponding yoke, the latch lever 82 is also moved upward until its shoulder 83 is lifted above the coacting shoulder 84. The spring 85 will pull the latch lever inward so that the shoulders will be in locking engagement. For the purpose of tripping this latch mechanism a suitable trip member 86 is provided on the outer vertical wall of

the cam as shown in Fig. 1. This trip member has an inclined surface engaging a correspondingly inclined surface 82^a on the lower end of the latch lever 82, whereby the 5 lower end is forced outward and the shoulder 83 moved out of engagement with the shoulder 84, so that the spring 78 may force the roller carrying member upward to lock the presser rod 64 as hereinbefore explained.

10 The top of the plunger 37 is provided with a head or abutment 37^b arranged to come in contact with the end of the lever 80 toward the limit of the downward travel of the plunger. The purpose of this is to release 15 the locking rollers 75 from tube 74, and thereby release the presser foot in case no bottle is in position to be crowned. Thus, the presser rod 64 is released from the locking device before the plunger has started on 20 its upward stroke. By this mechanism a crown in place in the throat of the crowning die will not be injured by the presser rod during the upward travel of the plunger.

The purpose of the latch device 82 hereinbefore described is to keep the locking rollers 75 out of action during the time that the corresponding capping plunger is traveling on the horizontal portion of the cam. This permits the plunger and presser rod 30 to be moved upward as a unit during the compensating action of the spring 30 and abutment block 24, thereby preventing injury to the crown during such compensating action.

35 Suitable mechanism is provided for supplying crowns to the plungers. In the present example, the capping die of each plunger is provided with a lateral opening in a well-known manner through which a 40 crown may be fed to the interior or throat of the die. In the best embodiment of the invention the crown-supplying mechanism is stationary and has a chute arranged to lead crowns to the respective plungers as 45 each plunger comes in register with the chute. In the example illustrated in the drawings, the means for supplying crowns comprises a hopper 87, Figs. 1 and 2, which is advantageously mounted on the front portion 50 of the head casing. This hopper device is arranged to deliver crowns one by one in proper position to the chute 88. For the purpose of driving the hopper mechanism and at the same time permitting the 55 front portion 1 to be removed from the rear portion 2 in a convenient manner, the drive shaft 89 of the hopper mechanism is provided at its rear end with a coupling 90, arranged to be engaged by two pins 91 pro-

60 jecting forward from a worm wheel 92 arranged to be engaged by a worm 93, Fig. 4, mounted on a vertical shaft 94, Fig. 2. At the lower end of this shaft is a pinion 95, in mesh with the annular gear wheel 60.

65 The shaft 94 and the worm wheel 92 are

carried by a standard 96 bolted to the cam housing 57. The pins 91 are so mounted as to be pressed yieldingly toward the coupling member 90. In the present example, this is done by attaching the pins 91 to a plate 97 carrying a central stud 98 projecting through a hole in the worm wheel 92 and having a head 99 arranged to bear against a helical spring 100 which surrounds the central stud 98 and bears at its other end 70 against the worm wheel. As a result of the construction just described, the rotation of the pinion 95 by the annular gear wheel 60 will rotate the worm wheel 92 and through the pins 91 will rotate the hopper shaft 89. 80 The front plate 89^a and the dial 89^b of the hopper mechanism, are driven from the shaft 89 by a ratchet wheel 89^c removably secured to the end of the shaft 89, and engaging a spring pawl 89^d connected to the front plate. By this arrangement, if a crown should become jammed in the hopper mechanism the pawl will ride over the ratchet wheel and thus allow the dial and front plate to remain stationary. The rear 90 wall of the dial has a series of lifting vanes 89^e for agitating the crowns within the hopper 87. The crowns are fed from the hopper mechanism one by one in the usual way and by the usual means.

The front portion 1 of the head casing and the attached hopper mechanism may be readily swung open or removed in the manner hereinbefore described, owing to the detachable connection between the coupling 90 and the pins 91. When the front portion 1 of the head casing is swung or put back into place, if the pins 91 are not in register with the opening in the coupling 90, the pins will be driven forward against 105 the action of the spring 100. By turning the shaft 89 by hand or by putting the machine in operation, which causes the rotation of the worm wheel 92, the pins 91 will be brought into proper alignment with the coupling and forced by the spring 100 into engagement with said coupling, thus properly coupling the shaft 89 and the hopper mechanism. The chute 88 is pivotally connected to the front part of the casing, as indicated 110 at 101, Fig. 2, so as to permit a slight adjustment of the lower end of the chute. This adjustment may be made in any suitable way, as for example, by attaching the lower end of the chute to a vertically movable member 102 arranged to be screwed up and down by a screw 103 carried by an arm 104 bolted to the front portion 1 of the casing, as indicated at 105.

The end of the bottom portion of the chute 125 88 is extended to a point where it will nearly reach the exterior of a capping die, so that the upper surface of the chute bottom will lie in line with the bottom of the opening in the throat, the end of the chute being in 130

the form of a movable member thereby preventing injury to the chute. This movable member is arranged to swing in two directions, viz, in a horizontal plane about a vertical axis, and, second, bodily in a vertical plane about a horizontal axis. In order to accomplish this result, the following construction may be employed. The movable member, indicated at 106 (Fig. 14) is 5 secured to a stud 107, (Fig. 15) having a head 108 flattened on one side. The stud 107 is rotatably mounted in a shoe 109 pivoted at 110 in a slot formed in the upper portion of the chute (see Fig. 16). The 10 upper part of the shoe 109 has a spring barrel containing a spring 11 surrounding a bolt 112 whose head 113 bears against the flattened side of the head 108. The shoe 109 is provided with a stud 114 projecting 15 laterally through the eye 115 of a bolt 116 having an adjusting nut 117 threaded on its lower end. The bolt 116 passes loosely through an enlarged opening in a lug 118 secured to the side of the chute 88. Between the lug 118 and the nut 117 a helical spring 119 is provided. It will be seen that if a crown at the end of a chute enters the opening of the capping die but is not positioned entirely within the throat of the die, 20 it will be carried by the orbital movement of the plunger against the latch or movable member 106. Hence, it will tend to swing the latch out of the way, about the vertical axis 107 of said latch. As soon as the head has 25 passed the latch 106, the crown will drop to the floor.

If at any time while a plunger is approaching the chute, the compensating action of the heads should take place, due to a bottle of abnormal size under the crowning plunger, the compensating movement would cause that plunger approaching the crown-chute to be elevated to a certain extent, as was hereinbefore explained. Consequently, 40 the lower part of the elevated plunger would contact with the end of the chute and the latch if these were rigid, but since the mouth of the opening to the throat of the capping die is flared downward sufficient 45 clearance will be obtained, thereby to enable the capping die to pass the bottom end of the chute even when in its slightly elevated position. Furthermore, the end of the latch 106 which would first be struck by 50 such an elevated plunger is inclined, as shown in Fig. 15, with the result that when struck by the die the latch and the shoe 109 will be swung on the pivot 110 against the action of the spring 119, thus permitting 55 the latch to swing out of the way of the die, as will be clear from Figs. 14, 15 and 16.

It will be understood that in the ordinary operation of the machine, the flow of the 60 crowns down the chute would tend to be continuous. To prevent such a flow, except at

the time when a capping head is in register with the end of the chute, a guard device 120, Fig. 19, is attached to the bottom bearing plate 15 of the cage. This guard device extends downward and has arc shaped walls 70 filling the spaces between the capping plungers, as will be clear from Fig. 19. If at any time it becomes necessary to stop the flow of the crowns down the chute, as, for example, when it is desired to inspect the mechanism, 75 a spring latch 121, Fig. 14, may be allowed to spring through a hole in the bottom of the chute so that its end will project into the path of the crowns and thereby hold them back. When operating at high speeds, 80 the effect of the centrifugal force due to the orbital movement of the plungers is to disturb the crown in its position in the throat carrier, with the result that at times it might be thrown from its seat. To overcome this, 85 the lower end of the presser rod 64 is made tubular to receive a spring 122 arranged to bear against a ring 123 through the center of which passes a pin 124 held by the presser rod. This pin allows a limited amount of 90 play of the ring in the end of the presser rod. The ring 123 can project slightly below the lower end of the presser rod and thus rest on a crown, against which it is forced lightly by the spring 122 (see Fig. 95 14), thereby pressing the crown against the crown seat in the die and holding it against displacement by centrifugal force.

A suitable packing 125 is provided around the lower end of the presser rod 64 as shown 100 in Figs. 1 and 14, this packing being forced up by a gland 126 screwed into the lower end of the plunger. The purpose of this packing is to guide the presser rod and at the same time prevent oil from flowing down 105 around the presser rod to the crowns.

In order to permit the abutment block 24 to seat itself quietly on its return to normal position after a compensating movement, the arm 25^b, Fig. 7, is connected to a 110 dash-pot mechanism of any suitable kind. In the particular embodiment shown in the drawings, this dash-pot mechanism is as follows: The end of the arm 25^b is slotted to receive a stud bolt 127 (see Fig. 7), which 115 is threaded into the lower end of the dash-pot standard 128 supporting a dash-pot cylinder 129 having an annular chamber 129^a connected by ports to the interior of the cylinder, as shown in Figs. 7, 8 and 9. In 120 the upper end of this dash-pot cylinder is secured a bushing 130 having passages 131. Within the bushing and cylinder is located a piston or plunger device 132 bolted to an arm 34^a carried by the tubular sleeve 34. 125 The movement of the abutment block 24 and of its connected arm 25^b causes a movement of the dash pot cylinder 129 relative to the plunger 132. The plunger is hollow at its upper end, as shown in Fig. 7, and is 130

provided with passages 133 arranged to register at times with the passages 131 in the bushing. Oil falling into the cavity of the piston 132 in a manner hereinafter described 5 will flow through the passages 133 and 131 when the same are in register and thence will flow into and through the chamber 129^a and through its ports to the bottom of the cylinder 129 and accumulate therein. The 10 lower surface of the plunger 132 is conical, as shown in Fig. 7. When the abutment 24 moves down it will draw the cylinder 129 downward and bring the passages 133 and 131 into register so that all the oil 15 in the upper part of the plunger will flow to the bottom of the cylinder. When the abutment rises under the influence of its spring the dash pot cylinder 129 will also rise and owing to the conical shape of the 20 plunger the oil in the bottom of the dash pot cylinder will rise and tend to flow out through the chamber 129^a and the passages 131 and 133 back to the cavity in the plunger 132. As the passages 131 and 133 gradually 25 pass out of register, there is a throttling action of this back flow of the oil, thereby checking the upward movement of the abutment. Just before the abutment 24 reaches its extreme upward position and contacts 30 with the top spider of the cage the passages 131 and 133 will be cut out of register with each other, thus preventing any further flow of oil through them. After this, the conical lower end of the plunger 132 tends to 35 drive the oil into the chamber 129^a and thereby creates pressure therein, thus checking the upward movement of the abutment 24.

A lubricating system is provided for the 40 whole apparatus by which oil is circulated from a suitable reservoir to the different parts of the apparatus, and back to the reservoir, as will be clear from the description hereinafter. So much of the lubricating 45 as pertains to the capping mechanism, will now be described.

The top of the head casing is provided with an oil inlet, as indicated at 134, Fig. 2, which may be supplied with oil in any 50 suitable manner, as, for example, by a pipe from an oil pump, as hereinafter described. This oil inlet is arranged to spray oil toward the center of the apparatus onto the rotating parts, so that it will flow downward 55 over all the parts and will enter suitable oil channels provided in certain parts. In the present example, the top of each plunger carries an oil cup 135, Fig. 5, arranged to catch some of the oil spray. In the present 60 example, the cup 135 is held to the top of the tubular stop rod 79 by means of a screw 136 having oil ducts connecting with the interior of the tubular stop rod. Just above the solid bottom of the stop rod 79 is a 65 transverse duct arranged to discharge out-

ward into grooves formed in the inner wall of the tube 74. The stop rod 79 is somewhat reduced in diameter above its lower end so as to leave a clearance space between its exterior surface and the interior of the upper 70 end of the tube 74, as will be clear from Fig. 5. By this arrangement the oil from the interior of the cup 135 can flow down the interior of the stop rod 79, up through the spaces between the tube 74 and the stop 75 rod, and then overflow down the outside of the tube 74 to the interior of the plunger 37. Near the bottom of the plunger is a duct 137, which leads to a space around the presser rod 64 just above the packing 125 80 (Fig. 2) so that the presser rod may be lubricated at this point. Any surplus oil passes through an opening from the duct 137 into a cup 138 carried by the outside of the plunger. This cup also serves to 85 catch any surplus oil which may flow down the outside of the respective capping plunger. The packing 125 at the bottom of the plunger serves to prevent any excess flow of oil to the capping die, and thus protects the crowns from being smeared with oil. 90

The cup 138 has at one side a pump cylinder 139, Figs. 48 and 49, connected with the interior of the cup by ports 140 and 141. 95 Within the cylinder is arranged a pump piston 142 held by a thimble 143 to the lower end of a tubular pump rod 144, whose upper end is threaded into an opening in the bottom bearing plate 15 of the cage. The 100 upper end of the thimble 143 is provided with a valve seat arranged to coact with a suitable valve, as, for example, the ball valve 145, whose upward play is suitably limited in any suitable way, for example, by a transverse pin 146. 105

As the plunger 37 reciprocates, the pump cylinder 139 is reciprocated relative to the stationary pump piston 142 and thereby oil is pumped from the cylinder to the top of the bottom bearing plate 15 of the cage, from whence it overflows into a collecting trough 147 and is led back to an oil reservoir in the bottom of the pedestal of the machine by a pipe 148. The port 140 connecting the cup 138 with the cylinder 139 serves to allow oil to flow from the cup into the bottom of the cylinder. If any oil leaks past the piston 142, it will flow back into the cup through the port 141 and then will return to the lower side of the pump piston by way of the port 140. 115

The cups 135 have sloping sides which deflect the excess of oil falling upon them and thus assist in distributing the oil to the rotating mechanism. Centrifugal force also assists in this distribution of oil, so that the cam 56 and cam rollers 45 and 46, as well as the bearings of the yokes and all gears, are well lubricated. 125

The head casing and its contained mechanism is arranged to be adjusted vertically on its support, while at the same time maintaining a connection with the driving mechanism. In the present example, the head casing with its contained parts, is mounted on a hollow pedestal 148 which has plane guide surfaces at the front and inclined ways 149 at the sides, as will be clear from Fig. 20.

10 The head casing has rearward extending flanges 150 and carries gibbs 151 arranged to occupy the spaces between the inclined faces of the flanges 150 and the ways 149. These gibbs are carried by bolts 152 which can be tightened to hold the head casing at any desired position, or may be loosened when it is desired to adjust the head casing up or down on the pedestal.

To the back of the head casing is secured 20 a gear-casing 153, Figs. 1 and 20, provided with bearings in which are mounted the idler gear pinion 62 and a drive gear 154. The idler gear 62 has a central opening through which passes loosely a screw 155 mounted in a removable boxing 156 at the top of the pedestal and engaging a nut 157 carried by a lug 158 on the rear wall of the head casing. The screw 155 has a worm wheel 159 fixed to its upper end, within the 25 boxing 156 and engaged by a worm 160 arranged to be operated by a hand crank 161, as will be clear from Fig. 1.

It will be obvious that by rotating the 30 crank 161 the screw 155 will be rotated and the head casing correspondingly moved vertically, the gear casing 153 and gears 62 and 154 moving with it.

The gear wheel 154 is splined to a vertical shaft 162 driven by suitable mechanism, 40 such, for example, as hereinafter described.

In the present example, the vertical shaft 162 is splined at the lower end to a stub shaft 163 mounted in a suitable boxing 164, and provided with a bevel gear wheel 165 arranged to be driven by a coacting bevel wheel 166 forming part of a transmission mechanism which will be more fully described hereinafter.

The stub-shaft 163 has its upper end 50 formed as a socket 167 into which the lower end of the vertical shaft 162 is received, as shown in Fig. 21, and in this socket are provided two keys 168 preferably cylindrical in cross-section, which are arranged to enter the key ways at the lower end of the vertical shaft 162. An annular plate 169 secured to the top of the stub-shaft 163 serves to hold these keys 168 in place. The upper end of the vertical shaft 60 162 projects slightly through an opening in the top of the pedestal, this opening being covered by a removable cap 170. By removing the cap the vertical shaft 162 may be removed by drawing it vertically upward.

55 The transmission mechanism, when the

vertical shaft is withdrawn, may be removed as an entirety from the pedestal. In order to permit this, the pedestal 148 has an opening in its rear wall, and the transmission mechanism has a casing 171 provided with a flanged portion 171^a arranged to extend over the outside of the rear wall of the pedestal, so as to close the lower part of the pedestal opening, the upper part of this opening above the transmission casing being closed by a removable cover plate 172 arranged to be locked in place by a spring latch device (Fig. 21). This spring latch device, in the present embodiment, comprises a rod 173 having its inner end bent at 70 right angles, so that it may engage the inner wall of the pedestal. The rod also has a head 173^a whose inner end is counter-bored to receive one end of a helical spring 174 surrounding the rod. The head is received in 75 a socket 175 formed in the cover plate in which the other end of the spring 174 is held. The rod has a pin 176 extending transversely of it and arranged to enter a notch in the inner wall of the cover plate. By pressing 80 inward on the head 173^a the pin 176 is released from its notch, whereupon the head may be rotated, thereby rotating the rod 173 and freeing its end from the inner wall of the pedestal. The cover plate 172 may then 85 be swung outward and lifted up, thus freeing it, so that it may be removed to give access to the interior of the pedestal. The lower end of the cover plate is held in place in any suitable way, as, for example, by allowing its lower end to rest in a groove in the upper part of the transmission casing. Suitable bolts are provided for holding the transmission case flanges to the pedestal, as 90 indicated, for example, at 177, Fig. 24.

95 The transmission casing carries a rearward projecting sleeve 178 on which is rotatably mounted a pulley 179 having a hub provided with an extension 180 whose interior serves as a clutch surface.

100 To the hub extension is secured a cap 181 which serves to enclose a clutch device which may be of any desired construction, but in the present embodiment of the invention is as follows:

105 Within the sleeve 178 is rotatably mounted a clutch shaft 182, Figs. 21 and 24, to which is secured a clutch spider 183 arranged to support a pair of segmental clutch shoes 184 held in line by guide studs 185 arranged to slide radially in sockets in the spider 183 and fixed to the clutch shoes 184. The outer ends of these studs 185 are counterbored to receive springs 186, and through 110 each spring and through each of the studs 185 passes a screw 187 threaded into the clutch spider. The screw heads bear against the springs 186 and thus tend to hold the clutch shoes 184 out of contact with the 115 clutch surface of the pulley hub.

For the purpose of expanding the shoes against the clutch surface of the pulley, two wedges 188, Fig. 25, are provided, these entering the space between the ends of the 5 clutch shoes. These wedges are secured to a disk 189, Fig. 26, having a long hub 190 which extends through the center of the cap 181 and enters a socket formed in the end of a pump driving shaft 191.

10 Through the center of the clutch spider 183 extends a tubular transmission gear shaft 192, Fig. 24, arranged to be secured to the clutch spider in any suitable way, as, for example, by keys, as shown in Fig. 25, and 15 by a nut 193, Fig. 24, threaded onto the end of the transmission shaft. The transmission gear shaft 192 is provided near its center with a circumferential groove into which enters a spring ring 194. Between this ring 20 and the shaft 182 of the clutch spider 183 are clamped a pair of ball bearing rings 195 and 196, separated by a spacer tube 197. The interior of the sleeve 178 carries coacting ball race-ways 198 and 199 between 25 which and the rings 195 and 196 are located the usual bearing balls. The front end of the transmission gear shaft is supported by ball bearings 200 in the front of the transmission gear casing, as shown in Figs. 21 30 and 24.

On the transmission gear shaft 192 are mounted a set of change gears 201 splined to the transmission gear shaft and arranged to be moved axially by a fork 202, Figs. 22, 35 and 24 extending from a slide 203, Fig. 23, operated by an arm 204 fixed to a rock-shaft 205 having polygonal ends either of which may be engaged by a wrench 206 insertible through holes in the side of the pedestal, as 40 will be clear from Figs. 22 and 23. The slide 203 is arranged to slide along a rod 207 fixed in the casing. The rod 207 has a number of rounded notches arranged to be engaged by a spring pressed pawl 208 carried 45 by the slide. By this means the slide is held at any one of the various positions to which it may be adjusted.

The respective change gears of the set 201 may be shifted into mesh with corresponding gears 209, 210 and 211 carried by a drum 212 splined to a drum 213 journaled in ball bearings, as shown in Fig. 21, one of which is supported on a stud 214 secured in the pedestal. To the inner end of the drum 55 shaft is fixed the bevel gear 166 meshing with the corresponding bevel gear 165 at the lower end of the stub-shaft 163.

A clutch rod 215, Figs. 21 and 24, extends through the tubular transmission shaft 192, 60 this rod being pinned to the long hub 190 of the disk 189.

The front end of the clutch rod 215 is engaged by a suitable actuating mechanism which, in the present case, comprises a 65 forked rocker-arm 216, Fig. 28, on a rock-

shaft 217 journaled in the casing and having ends projecting beyond the transmission gear casing and provided with lugs 217^a arranged to be engaged by the socket of a crank 218 which may be inserted from either 70 side of the machine through holes in the pedestal, as will be clear from Fig. 28. In the forked rocker arm 216 is trunnioned a collar 219 having an opening through which the reduced end of the clutch rod 215 passes 75 loosely. This reduced end is provided with stop collars 220 and 221 at each side of the trunnioned collar 219.

By means of the crank 218 the clutch rod 215 may be moved longitudinally to lock or 80 unlock the clutch mechanism, whereby the transmission gear shaft may be rotated by the pulley 179 or may be released therefrom and thereby stopped. In order to stop the shaft quickly a suitable brake device is connected to the clutch mechanism. In the present example, the rear end of the clutch rod 215 and the long hub 190 of the disk 189 are slotted transversely to receive a brake-arm 222 which carries brake shoes 223. At 90 its other ends, as shown in Figs. 21 and 27, these brake shoes are arranged to contact with a suitable brake facing 224 secured to a casing 225 projecting rearward from the pedestal.

95 For the purpose of rotating the disk 189 from the clutch spider 183, the latter is provided with two pins 226 projecting rearward into guide-sockets, indicated at 227, Fig. 24.

The pump shaft 191 is provided with a 100 slot at its front end, into which enters the brake-arm 222 whereby the pump shaft is driven from the disk 189. A part of the pump shaft is formed as an eccentric, on which is mounted an eccentric strap 228 to 105 which is connected a pump rod 229 whose lower end is connected by a loose connection in the usual way to a plunger 230 as will be clear from Fig. 29. The plunger is hollow and the pump rod is tubular. At the lower 110 end of the pump rod is mounted a valve 231 which can open upward, but closes downward.

The pump shaft 191 has an axial opening 115 communicating with the interior of the pump rod through a radial opening, as shown in Fig. 29. The axial opening also connects with two other radial openings leading to the bearings of the pump shaft, as will be clear from Fig. 21.

120 The plunger 230 moves in a pump cylinder 232 having an inlet port 233 opening to the outside of the cylinder and arranged to be closed by the plunger at a certain part of its downward movement. The lower end 125 of the pump cylinder is provided with a discharge port, to which is connected to main supply pipe 234 for oil, which leads to the top of the apparatus and is connected by a flexible pipe 235 with the oil inlet 134 of 130

the head casing. A suitable stop valve 236 is provided in this supply pipe near the oil pump. The pump cylinder also has a port near its bottom and controlled by a spring 5 pressed relief valve 237. The pump cylinder is located in a suitable part of the casing and is surrounded by a screen 238 to prevent clogging of the inlets to the pump cylinder. An extension of the casing indicated at 239, Fig. 1, has a lid 240 and a removable strainer cup 241, whereby oil may be poured into the casing and strained.

When the oil pump is operated by the rotation of the pump shaft, the oil is driven 15 out through the main supply pipe 234 and also a small part is forced up the tubular pump rod, thus oiling the bearings of the pump shaft. The main supply pipe discharges into the head casing, as has been explained hereinbefore, the connection through 20 the flexible tube 235 permitting the vertical adjustment of the head.

From the main supply pipe, a branch pipe leads to the interior of the pedestal and discharges onto the gear casing 153 which is arranged to hold enough oil to maintain a supply to the gears through oil holes as shown in Fig. 1; the surplus overflowing onto the vertical shaft 162 and being caught 30 at the bottom by a cupped portion of the bearing, which retains a sufficient supply to feed oil to the bearings through oil holes, as shown. The surplus overflows onto the transmission gearing and flows into the casing 35 of this gearing, from whence it flows through holes in the hub of pulley 179 and is thrown into the annular guard ring 243 and runs back to the reservoir at the bottom of the pedestal (see Fig. 21). From this 40 reservoir it may flow through the pipe 244, controlled by a stop cock 245, to the pump.

For the purpose of holding the receptacles to be operated on, and feeding them in proper timed relation to the capping plungers, a rotatable table is provided, this table being arranged to be adjusted vertically toward and from the head casing of the capping mechanism.

In the present embodiment of the invention, the table construction is as follows:

A bracket 246 is arranged to slide vertically on the pedestal, means being provided for adjusting and holding the bracket at any desired height within its limits of adjustment. In the construction illustrated, this means comprises a stationary screw 247 fixed at the lower end to pedestal, as shown in Fig. 31 and having its upper end extending into the bracket as shown. The threaded part of the screw is engaged by a nut device 248 having its periphery formed as a worm-wheel engaged by a worm 249, the nut device being rotatably mounted in a block 250 inserted in the bracket 246. The worm 65 249 has its shaft provided with a polygonal

end for engagement by a hand crank 251 by which the nut device may be rotated and the bracket 246 adjusted up and down on the pedestal.

The bracket is provided at its front with 70 a socket arranged to receive the central depending tubular leg 252 of a table support 253 having a pair of upwardly-extending annular ribs 254, the space between which forms an annular groove from which extend downwardly a plurality of draining holes 255.

The tubular leg 252 carries ball bearings, as shown in Fig. 31, in which is mounted rotatably a table shaft 256 whose upper end 80 is formed as a socket to receive the lower end of the vertical table driving shaft 22. The socket is provided with key ways to receive cylindrical keys 257 which enter corresponding key ways in the lower end of 85 the vertical shaft 22. The table shaft 256 has a flange 258 to which is secured a table 259 preferably having a separate top 260 of non-corrosive material, such as bronze, the top being secured in place by suitable 90 screws 261. The table is provided with a plurality of recesses to receive bottle-pads comprising a rubber cushion 262, a pad cover 263 on top of the same, and a thin steel bottom plate 264 beneath the rubber cushion. 95 Radial holes 265 extend from the bottom of the recesses to the periphery of the table, so that any liquid which may reach the bottle-pad will be quickly thrown off by centrifugal force. 100

The bottom of the table is provided with a series of downwardly extending annular ribs 266 coacting with the ribs 254, as shown in Fig. 31 to form baffles to prevent any liquid from reaching the bearings of the 105 table.

To the lower end of the vertical drive shaft 22 is removably secured a spool having a barrel 267 and upper and lower flanges, each of which is in the form of a star-wheel or ratchet-wheel, as indicated at 268 and 269, Figs. 31 and 42. The spaces between the teeth of these star-wheels are in alinement and are of such size and shape as to conform to the bottles to be capped. Spools of different sizes are employed for different sizes and shapes of bottles. The star-wheels 268 and 269 are so positioned that their bottle-receiving spaces will properly aline with the bottle-pads on the table 115 as will be clear from Figs. 41 and 42.

For the purpose of insuring the delivery of the bottles to the bottle-pads and retaining them in proper position to be capped, and then removing the capped bottles, a suitable guide mechanism is provided which, in the present apparatus, is as follows:

The table-support 253 is provided with an outwardly projecting flange 270 on which 130

rests a ring 271 having two radially extending arms 272 and 273, Figs. 33 and 35. On the arm 272 is placed a guide block 274 provided with a T-slot to receive a T-headed bolt, as shown at 275, Figs. 33 and 34. By loosening this bolt, the guide-block 274 can be adjusted toward or from the center of the table, the guide block having a downwardly projecting rib 276 sliding in a groove 10 in a spacer block 277 pinned to the arm 272, so that the guide block 274 will always slide in a radial direction.

The guide-block 274 has a plurality of pairs of guide-openings, in which are slidably mounted a series of pairs of guide-rods 278, Fig. 33, each pair carrying a head 279. Each head is normally pushed toward the center of the table by a spring 280, as will be clear from Fig. 33. The movement 20 of each head and its pair of guide-rods is limited by suitable means, as, for example, by a collar 281 pinned to the outer end of one of the guide-rods.

The heads are of different sizes and shapes, 25 as shown in Fig. 41, so as to form a yielding guide wall which serves to force the bottles progressively toward the star-wheels 268 and 269.

A pair of deflectors are provided, one indicated at 282 for deflecting the incoming bottles toward the guide wall formed by the heads 279, and the other, indicated at 283, for deflecting the capped bottles from the bottle pads to the off-bearing conveyor.

35 These deflectors 282 and 283 are hinged together in a pintle post 284 extending upwardly from the arm 273 of the ring 271. The deflectors are connected by a spring 285 which tends to hold them in contact with 40 the barrel portion of the spool. The deflector 282 has an outwardly curved nose 286 which reaches to a point more remote radially from the axis of the spool than are the bottoms of the spaces between the teeth 45 of the star-wheels 268 and 269, but less remote than the ends of the teeth of such star-wheels, as will be clear from Fig. 42.

To the deflector 282 is pivoted a latch-device 287, yieldingly held outward in the 50 path of the incoming bottle by a spring 289, a suitable adjustable stop being provided, as indicated at 290, Fig. 42, to limit the outward swing of the latch-device.

To the guide-block 274 opposite the latch-device 287, there is bolted a lug 291, to which is pivotally secured a resilient guide arm 292 which may be clamped in any desired position by tightening its pivot bolt 293, Fig. 41.

60 The bottles fed onto the rotating table are forced past the latch 287 which yields to let each bottle pass it and then springs back to its normal position and thereby prevents any backward movement of the bottle. The

latch also tends to direct the bottle toward 65 the guide wall formed by the heads 279. The nose 286 of the deflector 282 insures the bottle contacting with this guide wall, the bottle being detained by the nose and the head opposite the nose until the corresponding teeth of the upper and lower star-wheels 268 and 269 come into contact with the bottle and sweep it past the nose, forcing the guide wall to yield slightly and carrying the bottle around to the capping 70 position. The conjoint action of the nose 75 286 of the deflector 282 and the yielding guide wall formed by the heads 279 is to insure the proper positioning of the bottle in the corresponding bottle pad. The bottle 80 is capped by the capping mechanism of the head as hereinbefore described and finally comes into contact with the deflector 283 which directs it off the table to the off-bearing 85 conveyor. The deflector 283 has a pivoted wing guide 294 which can be fixed by clamping its pivot bolt 295. This guide insures the arrival of the bottle on the belt of the off-bearing conveyor.

The feed conveyor and the off-bearing 90 conveyor are of similar construction, but are driven in opposite directions, as indicated by the arrows in Fig. 41.

While these conveyors may be of any suitable construction, it is important that 95 they be quick-running, yet reliable in order to properly supply filled bottles to the machine and remove capped bottles.

It is also important in connection with a capping apparatus of the present type that 100 the conveyors be capable of various adjustments, in order to fit the apparatus for use, under the different conditions encountered in actual practice.

In order to accomplish these results, the 105 conveyors are advantageously constructed and driven in the manner now to be described.

To the bottom of the bracket 246 is attached a gear casing having three main 110 parts, namely, a forked or angle member 296 having a body portion arranged to be connected to the bottom of the bracket 246 by a collar 297, as shown in Fig. 31, the angle member also having two branches extending at an angle to each other, as indicated in Fig. 32. To each branch is secured an extension, as indicated at 298 and 299, Fig. 32, each having a pair of shaft bearings 300 and 301, the bearings 300 being arranged to extend into the corresponding branch of the angle member 296. On the outer end of each extension is secured a head or cap, as indicated at 302.

The body portion of the member 296 also 125 is provided with a head or cap 303 between which and the end of the body portion is clamped a bearing member 304. The upper

end of the body portion carries another bearing member 305.

In the bearings of the body portion is mounted a common vertical conveyor drive-shaft 306 arranged to be driven from the table spindle 256 as, for example, by coupling the bottom of the table spindle to the top end of the common conveyor drive shaft 306.

- 10 On this drive-shaft are splined two bevel gear wheels, 307 and 308, which can be shifted vertically into and out of engagement with bevel gear wheels 309 and 310 fixed on horizontal shafts 311 and 312 15 journaled in the respective bearings 300 and 301 in the extensions 298 and 299. Each bevel gear 307 or 308 is arranged to be held in or out of engagement with the gears 309 and 310 by a pin, as indicated at 313, Fig. 31.
- 20 Each horizontal shaft 311 and 312 is provided on its outer end with a bevel gear 314, 315, which meshes with a corresponding bevel gear 316, 317, respectively, mounted on vertical shafts 318 each having a bevel gear 25 wheel 319 at its upper end, these shafts being journaled in bearing blocks 320, rotatably mounted in openings in the upper sides of the respective extensions, as will be clear from Fig. 31. The bearing blocks 320 are 30 larger in diameter at their lower ends than are their respective bevel wheels 316, 317, so that by withdrawing a bearing block from the hole in the extension, its bevel gear can also be withdrawn through said hole.
- 35 The bearing blocks are grooved and held in place by set screws, one of which is indicated at 321, Fig. 31.

Each bearing block has its upper end formed as a fork, as will be clear from Fig. 40 39, and in the arms of the fork are secured journal bearings 322, through which passes a shaft 323 provided at one end outside its fork with a sprocket wheel 324 and also provided inside the fork with a bevel gear 45 325 fixed to the shaft 323 and arranged to mesh with the corresponding bevel gear 319.

Each conveyor has a frame comprising a pair of side members 326, in which are mounted a pair of conveyor drums 327 and 50 328 around which pass an endless conveyor belt, 329. The drum at the outside end of each conveyor is arranged to be driven by a sprocket wheel 330 actuated by a chain 331 55 passing around the two sprocket wheels 330 and 324.

The side members of the conveyor frame have downwardly extending projections at each end, as shown in Fig. 37, and these are slotted, as shown. The slots at the end 60 nearest the machine receive the bearings 322 at the upper end of the bearing block 320, as will be clear from Fig. 39, whereby that end of the conveyor is supported. The slots at the outer end of the conveyor frame en-

gage trunnions 331 extending laterally from a head 332 mounted on the upper end of a jackscrew 333 provided with a hand wheel 334, as shown in Fig. 38. The jack-screw engages a nut 335 extending transversely through a stand 336 and held in place by a set-screw 337.

By the construction described the conveyor belt is driven by means of the sprockets and sprocket chain and the train of bevel gears from the vertical driven shaft 75 of the table. When the table is adjusted up or down by its adjusting mechanism, the outer end of the conveyor may also be adjusted by means of its jackscrew, to keep the conveyor belt substantially level with the 80 table.

At the outer end of each conveyor is secured a bracket whose top forms a tray 338 capable of holding a number of bottles, usually about three dozen. This tray is provided with sides and an end, as will be clear 85 from Fig. 41. The conveyor also has sides, as usual, and a guard 339, which covers the sprocket chain.

By shifting the bevel gears 307 and 308 in 90 an obvious manner, the direction of movement of both conveyor belts may be determined. By changing the bevel wheel 325 so as to engage one side or the other of the bevel gear 319, the direction of travel of the 95 corresponding belt may be determined.

For the purpose of protecting the vertical front guide faces of the pedestal, suitable removable sheet metal guard plates are provided, as shown in section in Fig. 24. These 100 guard plates comprise two sections, 340, each of which has an inwardly bent edge. The two sections are slidably connected, and are pulled toward each other by a spring 341. Each section has a knob or handle 342, 105 by which the sections may be slid apart against the action of the spring 341, to release the bent edges of the sections from the inclined ways of the pedestal.

The machine may be driven in any suitable way. In the example illustrated, it is driven by an electric motor 345 belted to the pulley 179. The motor is conveniently mounted on a shelf adjustable vertically in any suitable way, as, for example, by a screw 115 operated by a worm-wheel and worm provided with a hand crank, indicated generally at 346, Fig. 1.

From the description hereinbefore, it will be clear that in the present machine the distance between the table and the capping dies may be adjusted to suit bottles of various heights; the star wheels may be interchanged, to accommodate bottles of various diameters and shapes, and the speed of the machine 120 may be adjusted, for example, by adjusting the transmission apparatus, in order to work with bottles of various capacities and with

fillers of various makes. Hence, the machine is able to meet all the conditions of actual practice.

What is claimed is:

- 5 1. In a capping apparatus, the combination, with a plurality of capping plungers, a plurality of angularly and bodily movable connecting devices each connecting device being in engagement with its respective 70 plunger, and a common movable abutment device in engagement with all the connecting devices and serving as a fulcrum for the angular movement of each connecting device, of means for yieldingly holding the common 10 abutment device in a normal position, and means for moving the connecting devices whereby the plungers are actuated.
- 15 2. In a capping apparatus, the combination, with a plurality of capping plungers, a rack secured to each plunger, a rack device common to all the plungers and yielding means for holding the common rack device in a normal position, of a gearing for each plunger, said gearing engaging with 20 the rack of its respective plunger and with the common rack device, and means for moving each gearing bodily, whereby the plunger is operated.
- 25 3. In a capping apparatus, the combination with a plurality of capping plungers, a rack secured to each plunger, a rack device common to all the plungers and yielding means for holding the common rack device in a normal position, of a gearing for each 30 plunger, said gearing engaging with the rack of its respective plunger and with the common rack device, and a plurality of independent means, one for each plunger, each means being arranged to move its respective 35 gearing bodily whereby the plungers are operated in succession.
- 35 4. In a capping apparatus, the combination, with a capping plunger, of a rack secured thereto, a movable abutment device 40 provided with a rack, a gear wheel arranged to engage the rack on the abutment device and the rack carried by the plunger, a journal on which the gear wheel is loosely mounted, means for moving said journal bodily 45 parallel to the plunger, and yielding means tending to resist movement of the abutment device in the same direction as the plunger.
- 45 5. In a capping apparatus, the combination, with a plurality of orbitally movable 50 capping plungers, of an annular cam surrounding all of the capping plungers, and a plurality of angularly movable actuating devices one for each plunger, a centrally arranged abutment device with which each 55 actuating device engages, and a plurality of cam rollers running in contact with the annular cam and each arranged to operate one of the actuating devices to actuate the respective plunger.
- 60 6. In a capping apparatus, and in combination, bottle supporting means, a plurality of capping plungers movable relatively thereto, a cam roller associated with each capping plunger, a fixed cam track on which said rollers ride, a common compensating 70 spring for the several capping plungers, and means for successively bringing the capping plungers into operative relation with said spring.
- 65 7. In a capping apparatus, and in combination, bottle supporting means, a plurality of capping plungers movable relatively thereto, a cam roller associated with each capping plunger, a fixed cam track on which said rollers ride, a common compensating 75 spring for the several capping plungers, and means for successively bringing the capping plungers into operative relation with said spring to permit each plunger to yield against the spring in accordance with the 80 pressure set up between such plunger and the bottle to be capped.
- 70 8. In a capping apparatus, a plurality of reciprocable capping plungers, an additional reciprocable element, mechanism associated 85 with each of said plungers and operating with a fixed stroke, means whereby said mechanism tends to displace both the additional reciprocable member and the corresponding plunger, and means for opposing 90 the movement of said additional reciprocable member within the limits of a predetermined force.
- 75 9. In a capping apparatus, and in combination, bottle supporting means, a plurality of capping plungers movable relatively thereto, a cam roller associated with each plunger, a fixed cam track on which said rollers ride, a common compensating 95 spring for the several capping plungers, and means having a leverage action on said spring for successively bringing the capping plungers into operative relation with the spring.
- 80 10. In a capping apparatus, the combination, with a capping plunger, a capping die carried thereby, a bottle support, a presser rod within the plunger and having one end movable through the throat of the die, of a clutch device arranged to lock the presser 100 rod against relative upward movement with respect to the support, means independent of the plunger for unlocking the clutch device and holding it in its unlocked position, and means for releasing the clutch device to 105 permit it to lock the presser rod.
- 85 11. In a capping apparatus, the combination with a rotary table, a plurality of capping plungers arranged to move in an orbit above the table and in synchronism therewith, a capping die for each plunger, and means for reciprocating said plungers toward and from the table to cap bottles thereon, of a presser rod for each plunger, each 110 presser rod being arranged to come into con- 115 tact with the capping die.
- 90 12. In a capping apparatus, the combination with a rotary table, a plurality of capping plungers arranged to move in an orbit above the table and in synchronism therewith, a capping die for each plunger, and means for reciprocating said plungers toward and from the table to cap bottles thereon, of a presser rod for each plunger, each 120 presser rod being arranged to come into con- 125 tact with the capping die.
- 95 13. In a capping apparatus, the combination with a rotary table, a plurality of capping plungers arranged to move in an orbit above the table and in synchronism therewith, a capping die for each plunger, and means for reciprocating said plungers toward and from the table to cap bottles thereon, of a presser rod for each plunger, each 130 presser rod being arranged to come into con- tact with the capping die.

tact with the corresponding bottle during the capping of the bottle, means for locking each presser rod in contact with the capped bottle during a portion of the rotation of 5 the table, and means for releasing each locking means to allow the corresponding presser rod to release the bottle after the corresponding die is clear of the cap of such bottle.

12. In a capping apparatus, the combination, with a cage, a plurality of capping plungers mounted to reciprocate in said cage, a cam surrounding the cage, and a central shaft for said cage, of a casing comprising parts separable along a line of division, 10 said casing enclosing the cage, its attached parts and the cam, means for detachably attaching the cam to one of the parts of the casing, and a bearing for the shaft mounted at the line of division of the casing, whereby on opening the casing all of the contained parts may be withdrawn as a unit.

13. In a capping apparatus, the combination with a plurality of capping plungers, each having a die, and means for operating 25 the plungers, of a casing comprising parts separable along a line of division, said casing enclosing the capping plungers and their operating means, a crown-supplying mechanism attached to one of the parts of the 30 casing and removable therewith, and a chute for conducting crowns from said crown-supplying mechanism to the dies of the plungers.

14. In a capping apparatus, the combination with a plurality of capping plungers, 35 each having a die, and means for operating the plungers, of a casing comprising parts separable along a line of division, said casing enclosing the capping plungers and their operating means, a crown-supplying mechanism attached to one of the parts of the 40 casing and removable therewith, a chute for conducting crowns from said crown-supplying mechanism to the dies of the plunger, and a loose connection between said crown-supplying mechanism and the plunger-operating 45 means whereby the former is operated.

15. In a capping apparatus, the combination with a plurality of capping plungers, 50 and means for moving said plungers in an orbit, of a table-operating shaft arranged to be revolved by said plunger moving means, said plunger moving means and said shaft being adjustable vertically relatively 55 to each other, a rotary table connected to said shaft, and means for adjusting the plungers and the table vertically.

16. In a capping apparatus, the combination, with a reciprocating capping plunger, an oil-receiving cup attached thereto, and an oil-pump cylinder connected to said cup and arranged to receive oil therefrom, of a plunger within said cylinder, a hollow plunger rod connected to the plunger and 60 arranged to conduct oil from the pump cyl-

inder, means for holding the plunger rod stationary, and means for reciprocating the capping plunger.

17. In a capping apparatus, and in combination, a capping plunger, a capping die carried thereby, a bottle support, means for reciprocating said capping plunger with respect to the support, a presser rod having one end movable through the throat of the die, locking means tending to prevent upward movement of the presser rod, and means for releasing said locking means in case the capping plunger exceeds a predetermined stroke toward the bottle support. 70

18. In a capping apparatus, and in combination, a plurality of capping plungers, a rack secured to each plunger, a multi-faced abutment block, a rack on each face thereof, a gearing for each plunger, said gearing meshing with the rack on its respective plunger and the corresponding rack on the abutment block, 80 a spider secured to said abutment block, a spring mounted to bear against said spider, thereby to hold the abutment block in a normal position, and means for moving each gearing bodily, whereby the 85 plungers are operated.

19. In a capping apparatus, and in combination, a cage, a plurality of capping plungers mounted therein, a rack secured to each plunger, a multi-faced abutment block, a rack on each face thereof, a gearing for each plunger, said gearing meshing with the rack on its respective plunger and the corresponding rack on the abutment block, 95 a spider secured to said abutment block, a hanger bar suspended from said cage, a spring mounted between the lower end of said hanger bar and said spider, thereby to hold the abutment block in a normal position, and means for moving each gearing bodily, whereby the 100 plungers are operated.

20. In a capping apparatus, and in combination, a plurality of capping plungers, a rack secured to each plunger, a centrally arranged multi-faced abutment block, a rack on each face thereof, a gearing for each plunger, said gearing meshing with the rack on its respective plunger and the corresponding rack on the abutment block, a cam track 110 surrounding the capping plungers, a yoke for each plunger having a head in which the plunger is slidably mounted, cam rollers mounted on each yoke to ride in said cam track, and a journal on each of said heads 115 on which said gearings are mounted.

21. In a capping apparatus, the combination with a rotary table, a plurality of capping plungers arranged to move in an orbit above the table and in synchronism therewith, a capping die for each plunger, and means for reciprocating said plungers toward and from the table to cap bottles thereon, of a presser rod for each plunger, each presser rod being arranged to come into 125 130

- contact with the corresponding bottle during the capping of the bottle, a movable head, rollers loosely mounted therein, a presser rod extension for engagement by said rollers, and means for wedging said rollers against said extension to prevent relative upward movement of the presser rod with respect to the table. 5
22. In a capping apparatus, the combination with a rotary table, a plurality of capping plungers arranged to move in an orbit above the table and in synchronism therewith, a capping die for each plunger, and means for reciprocating said plungers toward and from the table to cap bottles thereon, of a presser rod for each plunger, each presser rod being arranged to come into contact with the corresponding bottle during the capping of the bottle, a movable head, rollers loosely mounted therein, a presser rod extension for engagement by said rollers, a member provided with inclined surfaces, and a spring tending to move the roller carrying head to wedge the rollers 10 between said extension and said inclined surfaces, thereby to prevent relative upward movement of the presser rod with respect to the table. 25
23. In a capping apparatus, the combination with a rotary table, a plurality of capping plungers arranged to move in an orbit above the table and in synchronism therewith, a capping die for each plunger, and means for reciprocating said plungers toward and from the table to cap bottles thereon, of a presser rod for each plunger, each presser rod being arranged to come into contact with the corresponding bottle during the capping of the bottle, a movable head, rollers loosely mounted therein, a presser rod extension for engagement by said rollers, a member provided with inclined surfaces, a spring tending to move the roller carrying head to wedge the rollers 15 between said extension and said inclined surfaces, thereby to prevent relative upward movement of the presser rod with respect to the table. 30
24. In a packaging apparatus, the combination with a rotary table, a plurality of capping plungers arranged to move in an orbit above the table and in synchronism therewith, a capping die for each plunger, and means for reciprocating said plungers toward and from the table to cap bottles thereon, of a presser rod for each plunger, each presser rod being arranged to come into contact with the corresponding bottle during the capping of the bottle, means movable to prevent relative upward movement of each presser rod with respect to the table, and means for moving said movable means to re- 5
- lease the presser rod, and means for holding 65 said releasing means in releasing position. 25. In a packaging apparatus, the combination with a rotary table, a plurality of capping plungers arranged to move in an orbit above the table and in synchronism 70 therewith, a capping die for each plunger, and means for reciprocating said plungers toward and from the table to cap bottles thereon, of a presser rod for each plunger, each presser rod being arranged to come 75 into contact with the corresponding bottle during the capping of the bottle, a movable head for each presser rod, rollers loosely mounted therein, an extension on each presser rod for engagement by said rollers, 80 a member provided with inclined surfaces, a spring tending to move the roller carrying head to wedge the rollers between said inclined surfaces and said extension, thereby to lock the presser rod against relative upward movement with respect to the table, a lever for moving said roller carrying head against its spring to release the presser rod, and a latch for holding said lever in releasing 85 position. 90
26. In a packaging apparatus, the combination with a rotary table, a plurality of capping plungers arranged to move in an orbit above the table and in synchronism therewith, a capping die for each plunger, and means for reciprocating said plungers toward and from the table to cap bottles thereon, of a presser rod for each plunger, each presser rod being arranged to come into contact with the corresponding bottle during 95 the capping of the bottle, a movable head for each presser rod, rollers loosely mounted therein, an extension on each presser rod for engagement by said rollers, a member provided with inclined surfaces, a spring tending to move the roller carrying head to wedge the rollers between said inclined surfaces and said extension, thereby to lock the presser rod against relative upward movement with respect to the table, a lever for 100 moving said roller carrying head against its spring to release the presser rod, a latch for holding said lever in releasing position, and a trip for releasing said latch. 105
27. In a packaging apparatus, the combination with a rotary table, a plurality of capping plungers arranged to move in an orbit above the table and in synchronism therewith, a capping die for each plunger, and means for reciprocating said plungers 110 toward and from the table to cap bottles thereon, of a presser rod for each plunger, each presser rod being arranged to come into contact with the corresponding bottle during the capping of the bottle, a movable head for each presser rod, rollers loosely mounted therein, an extension on each presser rod for engagement by the rollers, a 120
- 125

member having inclined surfaces, a spring tending to move the roller carrying head to wedge the rollers between the inclined surfaces and said extension thereby to lock the 5 presser rod against relative upward movement with respect to the table, a lever for moving the roller carrying head against its spring to release the presser rod, and an abutment for operating said lever in case no 10 bottle is encountered by the presser rod.

28. In a packaging apparatus, and in combination, a capping mechanism comprising a reciprocating capping plunger, a bottle support, a relatively movable abutment, 15 bodily and angularly movable driven means, means for bodily moving said means with a fixed stroke, and means whereby the force of said movable means is applied to the capping plunger to lower the same toward the 20 bottle support as long as a predetermined pressure is not exceeded and is thereafter transferred to said abutment to move the latter and to release the plunger.

29. In a packaging apparatus, and in combination, a capping mechanism comprising a reciprocating capping plunger, a bottle support, a relatively movable abutment, a bodily and angularly movable driven element, means for bodily moving said driven 30 element with a fixed stroke, means for opposing relative movement of the abutment with a predetermined force, and connections between the driven element and the plunger and abutment respectively whereby the 35 driven element lowers the plunger toward the bottle support as long as a predetermined pressure is not exceeded and thereafter moves the abutment, the plunger being released.

40 30. In a packaging apparatus, and in combination, a capping mechanism comprising a reciprocating capping plunger, a bottle support, a relatively movable abutment, a bodily and angularly movable driven element, means for bodily lowering the driven 45 element with a fixed stroke, rocking connections between the driven element and the plunger and abutment respectively, and means for opposing relative movement of 50 the abutment with a predetermined force, whereby as long as said force is not exceeded the plunger is lowered toward the bottle support and thereafter the abutment is moved and the plunger released.

55 31. In a packaging apparatus, and in combination, a capping mechanism comprising a reciprocating capping plunger, a bottle support, a relatively movable abutment, means opposing movement of the abutment 60 with a predetermined force, a leverage device, means for operating the leverage device with a fixed stroke, and connections between the leverage device and the plunger, abutment and operating means respectively,

whereby the leverage device fulcrums on the 65 abutment to lower the plunger toward the bottle support as long as said predetermined force is not exceeded, and thereafter fulcrums on the plunger to move the abutment, the plunger being released from further movement.

32. In a packaging apparatus, and in combination a capping mechanism comprising a reciprocating capping plunger, a bottle support, a relatively movable abutment, a 75 rack on said plunger, a rack on said abutment, a bodily and angularly movable driven element having teeth meshing with each of said racks, means for moving said element bodily with a fixed stroke, and means for 80 opposing movement of the abutment with a predetermined force.

33. In a packaging apparatus, and in combination, a capping mechanism comprising plurality of reciprocating capping plungers, 85 bottle supporting means, a relatively movable abutment common to said plungers, a plurality of bodily and angularly movable driven elements, one for each plunger, means for bodily moving each of said driven elements with a fixed stroke, and means whereby the force of each of said driven elements is applied to its respective capping plunger to lower the same toward the bottle supporting means as long as a predetermined 95 pressure is not exceeded and is thereafter transferred to said abutment to move the latter and to release the plunger.

34. In a packaging apparatus, and in combination, capping mechanism including a 100 plurality of reciprocating capping plungers, bottle supporting means, a relatively movable abutment common to all of said plungers, a plurality of bodily and angularly movable driven elements, one for each 105 plunger, means for opposing movement of the abutment with a predetermined force, means for bodily lowering said driven elements in succession with a fixed stroke, and connections between each driven element and 110 its plunger and the abutment respectively, whereby each driven element lowers its plunger toward the bottle supporting means as long as a predetermined pressure is not exceeded and thereafter moves the abutment, 115 the plunger being released.

35. In a packaging apparatus, and in combination, capping mechanism including a reciprocable plunger, a bottle support, a 120 rack supported by the plunger, an additional support, a second rack supported thereby, one of said racks being relatively movable with respect to its support, a bodily and angularly movable driven element having teeth meshing with said racks, means 125 for bodily moving said driven element with a fixed stroke, and means for opposing relative movement of the relatively movable

- rack with a predetermined force, whereby the plunger is lowered toward the bottle support as long as a predetermined pressure is not exceeded and is thereafter released. 5
36. In a packaging apparatus, and in combination, capping mechanism including a plurality of reciprocating capping plungers, a relatively movable abutment, means 10 for opposing movement of the abutment with a predetermined force, a plurality of bodily and angularly movable driven elements, one for each plunger, means for bodily moving said driven elements with a fixed 15 stroke, connections between each driven element and the abutment and its plunger, respectively, whereby the driven elements lower the plungers as long as a predetermined pressure is not exceeded, and thereafter 20 move the abutment, and a dash pot for controlling the return of said abutment. 37. In a capping apparatus, the combination with a bottle support, a capping plunger having a capping die, and means 25 for reciprocating the plunger with respect to said support, of a presser rod arranged to come into contact with a bottle during the capping of the bottle, a movable head, rollers loosely mounted therein, a presser rod 30 extension for engagement by said rollers, and means for wedging said rollers against said extension to prevent relative upward movement of the presser rod with respect to the table. 35
38. In a capping apparatus, the combination with a bottle support, a capping plunger having a capping die, and means 40 for reciprocating the plunger with respect to said support, of a presser rod arranged to come into contact with a bottle during the capping of the bottle, a movable head, rollers loosely mounted therein, a presser rod 45 extension for engagement by said rollers, a member provided with inclined surfaces, and a spring tending to move the roller carrying head to wedge the rollers between said extension and said inclined surfaces, thereby to prevent relative upward movement of the presser rod with respect to the table. 50
39. In a capping apparatus, the combination with a bottle support, a capping plunger having a capping die, and means 55 for reciprocating the plunger with respect to said support, of a presser rod arranged to come into contact with a bottle during the capping of the bottle, a member provided with inclined surfaces, a spring tending to move the roller carrying head to wedge the rollers between said inclined surfaces, thereby to prevent relative upward movement of the presser rod with respect to the table, and means for moving 60 the roller carrying head in the opposite direction to release the parts. 65
40. In a capping apparatus, the combination with a bottle support, a capping plunger having a capping die, and means 70 for reciprocating the plunger with respect to said support, of a presser rod arranged to come into contact with a bottle during the capping of the bottle, means movable to prevent relative upward movement of the presser rod with respect to the support, means for moving said movable means to release the presser rod, and means for holding 75 said releasing means in releasing position. 80
41. In a capping apparatus, the combination with a bottle support, a capping plunger having a capping die, and means 85 for reciprocating the plunger with respect to said support, of a presser rod arranged to come into contact with a bottle during the capping of the bottle, a movable head, rollers loosely mounted therein, a presser rod extension for engagement by said rollers, a member provided with inclined surfaces, a spring tending to move the roller carrying head to wedge the rollers between said extension and said inclined surfaces, thereby to prevent relative upward movement 90 of the presser rod with respect to the table, a lever for moving said roller carrying head against its spring to release the presser rod, and a latch for holding said 95 lever in releasing position. 100
42. In a capping apparatus, the combination with a bottle support, a capping plunger having a capping die, and means 105 for reciprocating the plunger with respect to said support, of a presser rod arranged to come into contact with a bottle during the capping of the bottle, a movable head, rollers loosely mounted therein, a presser rod extension for engagement by said rollers, a 110 member provided with inclined surfaces, a spring tending to move the roller carrying head to wedge the rollers between said extension and said inclined surfaces, thereby to prevent relative upward movement of the presser rod with respect to the table, a lever for moving said roller carrying head against its spring to release the presser rod, a latch for holding said lever in releasing position, and a trip for releasing 115 said latch. 120
43. In a capping apparatus, the combination with a bottle support, a capping plunger having a capping die, and means 125 for reciprocating the plunger with respect to said support, of a presser rod arranged to come into contact with a bottle during the capping of the bottle, a member having inclined surfaces, a spring tending to move the roller carrying head to wedge the rollers between said extension and said inclined surfaces, thereby to prevent relative upward movement of the presser rod with re-

spect to the table, a lever for moving the roller carrying head against its spring to release the presser rod, and an abutment for operating said lever in case no bottle 5 is encountered by the presser rod.

44. In a capping apparatus, the combination with a capping plunger, of an angularly and bodily movable connecting device in engagement with said plunger, a movable 10 abutment device in engagement with said connecting device and serving as a fulcrum for the angular movement thereof, means for yieldingly holding the abutment device in a normal position, and means for moving

the connecting device bodily whereby the 15 plunger is actuated.

45. In a capping apparatus, the combination with a capping plunger, of a rack secured to the plunger, a rack device and yielding means for holding said rack device 20 in a normal position, of a gearing meshing with said racks, and means for moving said gearing bodily whereby the plunger is actuated.

In testimony whereof, I have hereunto 25 set my hand.

CONSTANT J. KRYZANOWSKY.
